INVENTOR

Attorney

UNITED STATES PATENT OFFICE.

WILLIAM V. YOST, OF WEST DECATUR, PENNSYLVANIA.

ROLLER-SKATE.

SPECIFICATION forming part of Letters Patent No. 363,716, dated May 24, 1887.

Application filed March 31, 1887. Serial No. 233,198. (No model.)

To all whom it may concern:

Be it known that I, WILLIAM V. YOST, a citizen of the United States of America, residing at West Decatur, in the county of Clearfield and State of Pennsylvania, have invented certain new and useful Improvements in Roller-Skates; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to that class of devices known as "pedicycles" or "pedomotors."

The object of the invention is to so construct a single-wheel pedicycle as to prevent the rearward movement of the wheel during the forward thrust or stroke of the foot, and also to so support the rim of the wheel when a weight is borne by the foot-plate as to relieve the spokes of strain. These and minor objects 20 are attained by the construction illustrated in the accompanying drawings, wherein—

Figure 1 is a side elevation of a pedicycle embodying my improvements. Fig. 2 is a similar view, looking from the other side. Fig. 30 3 is a vertical section.

The wheel consists of a hub, A, from which extend curved radial spokes B, united at their outer ends to the outer sides of the rim or felly C. The hub is at its outer end preferably in line with the outer curve of the spokes B and extends inward to about the inner edge of the felly, the inner end being cone-shaped to fit a cone-socket, d, formed about midway of the length of the leg-piece D. This leg-piece D 35 is curved outwardly from its center to lie within the curve of the spokes B, and is fitted at the lower end with a foot-plate, E, designed to project on either side of the felly, and provided with a friction-roller, e, traveling upon the inner surface of the felly. This foot-plate E is provided at the toe with a pawl, e', positioned to engage ratchet-teeth c formed on one edge of the felly, the purpose of this arrangement being to prevent the wheel from making 40 a retrograde movement. The heel of the foot-plate is provided with a downwardly and rear-

wardly extending spur, e", forming a drag-brake to arrest the forward movement of the wheel when occasion may require.

The upper end of the leg-piece B is fitted 55 with a strap, by means of which said leg-piece may be secured to the leg of the wearer below the knee, and the foot-plate is also provided with straps or other devices, by means of which said plate may be secured to the foot of the 60 wearer.

The wheel, hub, and leg-piece are connected by a bolt, d', which serves as the journal on which the wheel revolves, and I prefer that said bolt be provided with a coned head, forming, in connection with the coned socket of the leg-piece, two coned surfaces upon which the wheel revolves, the bolt being capable of longitudinal adjustment to take up wear, and to this end fitted with a jam-nut, d".

The spokes, or both the spokes and felly, 70 may be made of spring metal to take up vibrations and jar caused by traveling over uneven surfaces, and the felly may be provided with a rubber tire to further cushion shocks 75 and jars. In constructing the spokes, or spokes and felly, of spring metal I prefer that the friction-roll carried beneath the foot-plate be not in constant contact with the inner surface of the felly, but be brought in contact therewith to take strain from the spokes 80 and felly upon encountering an obstruction in the surface traversed.

I claim—

1. The combination, substantially as described, of the wheel having curved spokes, the leg-piece provided at its lower end with a foot-plate overhanging the felly, and the journal-bolt connecting the wheel with the leg-piece.

2. The combination, substantially as described, of the wheel consisting of a felly provided with inwardly-facing ratchet-teeth, and a hub provided with curved spokes united to the felly at one side, and the leg-piece connected 95 to the hub by a journal-bolt and provided at its lower end with a foot-plate fitted with a pawl to automatically engage the ratchet-teeth of the felly.

3. The combination of the wheel constructed 100 substantially as described, the leg-piece connected with the wheel by a journal-bolt, and

the foot-plate secured to the lower end of the leg-piece and fitted at the heel with a rigid drag and at the toe with a pawl.

4. The combination, with a wheel constructed as described, of the leg-piece, the foot-plate secured to the lower end of the leg-piece, the friction-roll, pawl, and drag carried by the foot-plate, and a journal-bolt connecting the leg-piece with the wheel.

10 5. The combination, substantially as de-

scribed, of the leg-piece provided with a coned socket, the wheel, and the journal-stud provided with a coned head.

In testimony whereof I affix my signature in presence of two witnesses.

WILLIAM V. YOST.
